UNITED STATES PATENT OFFICE

2,330,789

SAFETY CATCH FOR BAR PINS OF
BROOCHES AND THE LIKEQuirino Chiappinelli, Providence, R. I., assignor
of one-half to M. E. Proctor, New Haven,
Conn.

Application November 19, 1942, Serial No. 466,182

5 Claims. (Cl. 24—158)

This invention relates to a safety catch or lock for bar pins of brooches, badges, and the like.

The relative inexpensiveness of many brooches, badges, and similar ornaments requires that the attaching structures thereof be of maximum simplicity while at the same time being efficient in their intended uses.

While safety locks or catches for bar pins are well known and of diversified forms, prior structures of this general character—such, for example, as disclosed in the patents to G. H. Tilford, No. 1,274,630, August 6, 1918; C. A. Goozey, No. 1,321,621, November 11, 1919; and J. Pejchar, No. 1,410,592, March 28, 1922—failed to meet the requirements of maximum simplicity and would accordingly not be well adapted to the inexpensive ornament structures even though they may be efficient in operation.

It is accordingly a primary object of this invention to provide an improved safety catch or lock for bar pins which overcomes this particular objection to such prior constructions.

A further object of the invention is the provision of a safety catch or lock for bar pins which comprises only two highly simple, relatively movable parts whereby it is inexpensive of manufacture and due to its marked simplicity will not be liable to become inoperative even after a long period of use.

A still further object of this invention is the provision of a safety catch or lock for bar pins which is capable of being expeditiously assembled and united with the body portion of a brooch, badge, or the like.

For a more complete understanding of the nature and objects of this invention, reference will be had to the following detailed description, taken in connection with the accompanying drawing, wherein:

Figure 1 is an edge elevational view of a brooch, badge, or the like disclosing the application of my invention in accordance with a preferred embodiment thereof.

Fig. 2 is a top plan view of the structure illustrated in Fig. 1.

Fig. 3 is a perspective view of a catch member embodied in the improved safety catch or lock.

Fig. 4 is a similar view of a locking member embodied in the improved safety catch or lock.

Fig. 5 is an elevational view of the catch member with the locking member in unlocking position and having the near wall thereof removed for more clearly showing the cooperating slot arrangement.

Fig. 6 is an elevational view showing the locking member in pin shank locking position.

Referring now in detail to the drawing, B designates a brooch, badge, or like ornament having a bar pin P which is pivotally connected at the butt end thereof by means of a suitable pivot mounting M, which may desirably be of the character disclosed in my co-pending application Serial No. 466,181 filed November 19, 1942. 10 The penetrating end of the pin P cooperates with a safety catch or lock L which forms the subject-matter of this application.

The safety catch or lock L includes a catch member 10 and a cooperating locking member 11. 15 The catch member 10 is of generally rectangular form of moderate thickness and is adapted to be soldered or otherwise rigidly secured to the brooch or badge B in the approximate position illustrated in Figs. 1 and 2.

The catch member 10 is provided with an arched pin-receiving slot 12 which, as shown, enters through one edge thereof and terminates in a rounded closed end centrally of and adjacent the top of the catch member.

25 The locking member 11 is of generally box configuration open at the bottom and having a closed top 13, opposed solid side walls 14 and 15 and opposed walls 16 at right angles to walls 14 and 15. Each wall 16 is provided with a slot 17 opening through the bottom edge of the wall and terminating in a rounded closed end for conformity with the closed end of catch slot 12 when the locking member is in closed position, as in Fig. 6.

30 The locking member is so relatively proportioned with respect to the catch member that the side walls 14, 15 and 16 engage the corresponding vertical walls of the catch member, preferably under more or less friction, and the

40 wall 15 of the locking member terminates in a lug 18 which, as shown in Fig. 4, is, prior to assembly of the catch and locking members, coplanar with the wall 15 and which, after assembly, is adapted to be bent inwardly of the open end of slot 12 for alternate engagement with the upper and lower walls of the slot, as is clearly shown in Figs. 5 and 6.

45 As indicated in Fig. 5, the locking member 11 is capable of being drawn upwardly on the catch member 10 until lug 18 engages the top wall of slot 12, in which position the slots 12 and 17 are in communication and in which position the pin P may readily enter slot 12 and be drawn to the rounded closed end thereof to the position in Fig. 6.

After thus having admitted the pin into the slot of the catch member, the locking member is drawn downwardly until lug 18 engages the lower wall of slot 12, in which position the entrance to the catch member slot 12 is closed and the pin accordingly locked against inadvertent displacement from within the catch member slot.

It will be seen that the improved safety catch or lock includes only two structural elements and that such elements are exceptionally simple in structure, whereby the complete device is capable of being manufactured at low cost, is durable, efficient in operation, and is not liable to become inoperative as is the case with prior complicated devices of this general character.

While I have disclosed but a single specific embodiment of my invention, such is to be considered as illustrative only, and not restrictive, the scope of the invention being defined in the subjoined claims.

What I claim and desire to secure by U. S. Letters Patent is:

1. A safety catch or lock for bar pins comprising a catch member of generally rectangular form in side elevation, a curved pin receiving slot in said member opening through one edge thereof and having a rounded closed end, and a locking member of generally box-like formation having an open end slidably mounted on said catch member, opposed side walls of said locking member having laterally alined slots opening through the open end of the locking member, the open ends of said last slots communicating with said first slot in one position of said locking member on said catch member, and the closed ends of all of said slots being in lateral registry in another position of said locking member on said catch member.

2. The structure according to claim 1, together with means carried by said locking member and engageable with opposed walls of said first slot for limiting sliding movement of said locking

member on said catch member in each of said positions.

3. A safety catch or lock for bar pins comprising an upright catch member of generally rectangular formation having a curved pin-receiving slot opening through one edge thereof and having a curved closed end, and a locking member of generally box-like formation with an open lower end slidably mounted on said catch member, laterally alined vertical slots in opposed side walls of the locking member opening through the open lower end thereof and having rounded closed ends, the last named slots intersecting the first slot and the open ends of the last slots communicating with the open end of the first slot in one position of said locking member on said catch member to admit a pin into said slots.

4. The structure according to claim 3, together with means for limiting the movement of said locking member to said position, said means further limiting movement of said locking member to another position in which said open ends are out of communication and said rounded closed ends of all of said slots are in transverse registry.

5. In a device of the character described, a catch member secured to a brooch or the like and extending vertically above same, an upwardly directed slot in said member opening through one edge thereof, a locking member vertically slidably on said catch member and having laterally alined vertical slots intersecting said first slot at opposite sides thereof and having open lower ends, and a lug carried by said locking member engageable with the upper and lower walls of said first slot for limiting movement of said locking member on said catch member to positions in which the open ends of all of said slots are in and out of communication respectively.

QUIRINO CHIAPPINELLI.
